UNITED STATES PATENT OFFICE.

ERNEST MARKLEY, OF EVANSTON, ILLINOIS, ASSIGNEE OF ONE-HALF TO DRYING SYSTEMS INC., OF CHICAGO, ILLINOIS, A CORPORATION OF ILLINOIS.

AIR-FILTER DRIVE.

Application filed September 20, 1926. Serial No. 136,655.

This invention relates to improvements in air filters and the like, and more particularly to improved means for controlling the driving mechanism of such filters as the moving belt type, wherein a metallic foraminous belt is mounted on sprockets and extends across the air stream, with the lower end of the belt immersed in an oil bath for cleaning the belt, removing the dust, and 10 re-oiling the surfaces.

In such air washing apparatus it is found that the newly cleansed belt is inefficient, and that the highest efficiency is obtained by leaving the belt in the air stream until the 15 belt is well coated with dust. Accordingly, a slow, intermittently operating drive is supplied, which moves the belt, for example one-sixth of the length at each operation. The result is that a newly cleansed portion 20 of the belt is in the air stream at one side, and the portion which has been in the stream the longest is directly opposite. The periods in which the portions on the one side have been in the air stream increase as the 25 periods of the portions directly opposite decrease, with the result that an even effect is obtained throughout the air channel.

Heretofore, drives controlled by clock-work timing devices and intermittent gearing have been used. The belt was moved at 30 fixed time intervals and obviously no allowance was made for changes in the amount of air drawn through the filter.

The main objects of this invention are to 35 provide a more simple and reliable method of moving the screen, and to provide such means controlled directly by the air stream so that the screen is moved more nearly in proportion to the amount of air which is 40 passed through.

An illustrative embodiment of this invention is shown in the accompanying drawings in which:—

Figure 1 is an elevation of the air cleaning system.

Fig. 2 is an end elevation of the reduction gear housing and cam with a diagram of the electrical connections.

In the drawings, the air is drawn through 50 the filter unit 1 by means of the rotary blower 2, driven by the motor 3.

The filter unit comprises a housing 4 in which are mounted the horizontally disposed shafts 5. The shafts are provided 55 with wheels 6 on which are mounted the fil-

ter screen 7 which comprises an endless foraminous metallic belt.

Mounted on the outer end of the upper shaft 5 is a worm wheel 8 which meshes with a worm 9, secured on the end of the screen 60 driving motor 10. The motor is operated a sufficient length of time to turn this belt wheel 6 approximately one-half a revolution and then stop.

The housing 4 is apertured at either side, 65 the one aperture 11 being for admitting air, and the other aperture being connected to the intake of the blower 2. The aperture 11 is preferably reduced to circular form to confine the air stream to the circle of the 70 screen motor controlling fan 12, which is mounted in the housing of the speed reduction unit 13, supported on the frame 14.

The speed reduction unit 13 may be of any well known type suitable for effecting a 75 very large reduction from the fan shaft 15 to the cam shaft 16, mounted on the opposite side of the housing and positively connected to the shaft 15.

A switch lever 17 is centrally pivoted on 80 the housing of the reduction unit 13, and carries a mercury bulb screen motor switch 18 on the outer end, while the inner end 19 bears against the surface of the cam 20, secured on the shaft 16. The cam 20 has a 85 lobe 21 which, at each revolution of the cam 20, contacts with the end 19 of the switch lever 17 and closes the normally open switch 18 for a short arc of movement of the cam.

The switch 18 controls the screen motor 10: 90 as shown in Fig. 2 the switch 18 is connected in series with the motor 10 to the supply lines A through the main hand controlled switch 22. The supply motor 3 is also connected behind the main switch 22.

In the construction described, the fan 12 is operated whenever the supply fan 2 is running, and the speed of the fan 12 is proportional to the amount of air drawn through the filter 1. Intermittently the 100 screen motor switch is operated to turn a new section of the filter screen 7 into the air stream and then opened when the lobe 4 moves away from the lever end 19.

If the supply motor 3 is shut off while the 105 lobe 21 is on the end of the lever 17, the screen motor is also stopped because the two motors are both behind the main switch. Otherwise, the screen motor would continue to run until the air stream was re-started; 110

but, with the above provision made, the movement of the screen is stopped until the filter is again started, then the movement of the screen is completed.

5. While but one specific embodiment of this invention has been herein shown and described, it will be understood that numerous details of the construction shown may be altered or omitted without departing from 10 the spirit of this invention as defined by the following claims.

I claim:

1. In an air filter, a movably mounted filter screen, a motor for moving said screen, 15 a fan mounted in the path of the air passing through said screen and driven thereby, and a switch for said motor controlled by the fan.

2. In an air filter, a movably mounted filter screen, a motor for moving said screen, a 20 fan mounted in the path of the air passing through said screen and driven thereby, a switch for said motor, and means positively operated by said fan for controlling said 25 switch.

3. In an air filter, a movably mounted filter screen, a motor for moving said screen, 30

a fan mounted in the path of the air passing through said screen and driven thereby, a switch for said motor, and a cam positively 35 operated by the fan for controlling said switch.

4. In an air filter, a movably mounted screen, a motor for moving said screen, a fan operated by the air currents passing 35 through said screen, and means positively operated by said fan for intermittently operating said motor.

5. In an air filter, a movably mounted screen, a motor for moving said screen, a fan operated by the air currents passing through said screen, a cam positively driven by said fan, said cam having a lobe, and a motor switch operated by said lobe. 40

6. In an air filter, a movably mounted screen, a motor for moving said screen, a fan operated by the air currents passing through said screen, a cam positively driven by said fan and a motor switch intermittently operated by said cam. 45 50

Signed at Chicago this 10th day of September, 1926.

ERNEST SZEKELY.
